FLAG HOLDER

Charles H. Forbell, New York, N. Y., assignor to
The Flag in Every Home Committee, Inc., New
York, N. Y.

Application May 8, 1942, Serial No. 442,144

11 Claims. (Cl. 116—173)

The present invention is concerned with ornamental means for mounting a flag against the wall of a room in such manner as to simulate the appearance thereof as mounted upon a flagstaff.

It is among the objects of the invention to provide a simple, inexpensive and ornamental flag holder capable of being mounted against the wall by means of a picture hook, and so constructed as to cause the flag to hang free symmetrically and to simulate its appearance in hanging relation upon a flagstaff.

Another object is to provide a device of the above type which affords means for mounting the flagstaff finial with the pendant flag either upon the moulding of a room or alternatively upon a wall picture hook.

In the accompanying drawing in which are shown one or more of the various possible embodiments of the several features of the invention,

Fig. 1 is an elevational view showing the flag installed and pendant from the flag holder unit therefor mounted on the moulding of a room,

Fig. 2 is a sectional view on a larger scale taken on line 2—2 of Fig. 1,

Fig. 3 is a rear view of the hanger showing the flag retained thereby,

Fig. 4 is a plan view of the hanger blank that makes up the combined flag holder and moulding support,

Fig. 5 is a rear view showing the setting for mounting on a moulding and showing the hanging of a flag equipped with a grommet,

Fig. 6 is a view similar to Fig. 3 showing the device set for mounting on a wall picture hook,

Fig. 7 is a rear view of a flag hanger of modified form, and

Fig. 8 is a sectional view taken on line 8—8 of Fig. 7.

Referring now to the drawing, the flag holder unit preferably embodies a substantially conventional flagstaff finial 10 which may be molded from suitable inexpensive plastic material and which may be of conventional design, illustratively shown as a spread-wing eagle resting on a ball. A support or hanger member desirably a blank 11 of fiber is attached, as for instance, by brads 13 to the rear of the finial, and upon a boss 14 integrally moulded therewith. The lower part of the hanger 11 has an upstanding holding tongue 12 preferably struck out of the blank, which is also cut away at 15 laterally of the tongue at and above its root 16, the tip of the tongue constituting a clasp by coaction with the body of the blank from which it is struck.

The lower part of the finial which conceals the hanger from view is spaced from the latter by reason of the boss 14.

The corner of a flag 17 may be introduced

55

through the slots 15 and over the tip of the tongue 12 which latter grips and holds the flag without mutilation thereof against the corresponding edge of the hanger body 11. The flag will hang symmetrically, as shown, from its upper staff corner. It will appear to be mounted directly below the ball of the finial and will appear to be mounted upon a flagstaff that happens to be concealed from view by the draping of the flag, as best shown in Fig. 1.

The support member 11 is desirably equipped with unitary lateral hinged wings 18 and 19 that have notches 20 at the lower edges thereof which may be retained folded down against the body of the holder by either end of a tab 21 pivotally mounted against the finial by means of the brad 13 which extends therethrough.

In mounting the unit by means of a wall picture hook such as shown at 22 in Fig. 6 the tab 21 is so positioned about its pivot 13 as to expose the wider perforated end 23 thereof above the boss 14, the lower or narrower end of the tab serving as the retainer, as shown in Fig. 6 to keep the moulding hanger wings 18 and 19 flat against the boss 14 so that the finial may be retained flush against the wall, and suspended from the tab 21 which serves as the finial hanger.

In Figs. 1 to 3 is shown the arrangement or setting of the support member for mounting the flag from a moulding 24. To this end the tab 21 is turned to release the wings 18 and 19 so as to permit them to extend rearward from the finial as best shown in Fig. 3, with the tab 21 in idle position therebetween, so that the wings may serve as finial hanging hooks to straddle the moulding.

In the embodiment of Fig. 5 is shown the mounting of a flag equipped with a grommet 25. Desirably, the grommet band 26 would be turned back and secured to the flag by means of stitching 27. The corner of the flag being inserted between the finial 10 and the flag hanger, the grommet 25 is passed over the top of the flag hanging finger 12 and pressed downward thereon as shown.

Manifestly, the wings 18 and 19 could be omitted if the device is to be used only for hanging by means of a picture hook, or the tab 21 could be omitted if the device is to be used only for hanging the flag from a moulding. The device as shown is preferred because it admits of a choice in manner of hanging the flag against the wall.

In the embodiment of Figs. 7 and 8 is shown a flag holder, with the same finial 10 as in the other embodiment. The support member is desirably a flat blank 11', which has the finger 12' corresponding to that shown in the other embodiment for gripping the corner of the flag or mounting the grommet thereof. The root of

60

finger 12' is shown however as below the slots 15' to afford sufficient yield for the tongue since the support member 11' is desirably of stiffer material than the support member 11 of the other embodiment. The relatively rigid support member 11' is devoid of the hinging wings shown in Figs. 3, 5 and 6 for mounting upon a moulding. It has, however, at the upper end thereof, the aperture 23' for hanging the finial by means of a picture hook exposed above the boss 14' but concealed behind the finial. The support member 11' is equipped with a pair of parallel short transverse slots 28 and 29 to permit introduction therethrough as shown, of a conventional moulding picture hook 30, the hook end of which is threaded through the slots 29 and 30 to protrude rearward from the hanger member with its tail 31 thereagainst. The hook, if furnished as a pre-assembled part of the unit would be readily removable therefrom where the unit is to be hung by the ordinary wall picture hook.

As many changes could be made in the above article and many apparently widely different embodiments of this invention could be made without departing from the scope of the claims, it is intended that all matter contained in the above description, or shown in the accompanying drawing, shall be interpreted as illustrative and not in a limiting sense.

Having thus described my invention, what I claim as new and desire to secure by Letters Patent of the United States is:

1. A flag holder comprising a flagstaff finial having a unitary flag hanger of sheet material on the rear thereof provided with a struck out upstanding elongated tongue adapted at its free end to clamp the corner of a flag against the corresponding wall of the hanger without mutilating the flag, said holder having means for mounting the same against a wall.

2. A flag holder comprising a flagstaff finial having a unitary flat support member secured to the rear thereof concealed behind and spaced from the lower end of said finial, said support member having an upstanding flag hanging tongue struck out of the material thereof whereby the corner of a flag may be introduced between the finial and the hanger and retained in position by said tongue without mutilation of the flag, said support member having means for mounting the flag holder against a wall.

3. The combination of a flag and a holder unit therefor, said holder unit comprising a flagstaff finial having a support member of sheet material secured to the rear face thereof, said unit having a recess in front of the lower part of said support member, said member including an upstanding tongue struck out of the material thereof, the upper corner of said flag extending into said recess between the finial and the support member and being clamped in position by said tongue, said support member having means for mounting the unit against a wall.

4. The combination of a flag and a holder unit therefor, said unit comprising a flagstaff finial and a support member attached near its upper end to the rear of said finial and concealed thereby, said support member having means for mounting the same against a wall, and having a flag hanging tongue at its lower part, said unit having a recess in front of said flag hanging tongue, said flag having a grommet band turned inward and stitched to the body, the corner of said flag extending through said recess and the

upper part of said tongue extending into said grommet, said holder unit having means for mounting the same against a wall.

5. A unit for hanging a flag from the wall, said unit comprising a flagstaff finial and a support member attached to the rear of said finial and including a perforated element for hanging the same by means of a picture hook or the like, the lower part of said support member having means integral therewith for holding the upper corner of a flag without mutilation of the latter and permitting the same to hang from between the lower edge of the support member and the rear of the finial.

15. 6. An ornamental flag holder for retaining a flag in pendant position against a wall, said holder comprising a flagstaff finial, a support member concealed behind said finial and attached thereto and including a flag hanger, said support member having hook means extending rearward therefrom for mounting upon a moulding the finial and the associated support member with the pendant flag.

7. A flag holder comprising a flagstaff finial, 25 a support member attached to the rear of said finial and concealed thereby and including as a unitary part thereof a flag hanging tongue, said support member having unitary lateral wings with grooved notches at the lower edges thereof for mounting the finial with the pendant flag upon the moulding of a room.

8. The combination recited in claim 7 in which the lateral wings may be folded inward over each other and in which a finger member pivoted to 35 said support member may be positioned to retain the lateral wings in superposed relation, said finger having an aperture exposed above the hanger and behind the finial and serving for hanging the unit by means of a picture hook.

40. 9. A flag holder comprising a flagstaff finial, a relatively rigid flat support member secured to the rear of said finial and concealed thereby, and having flag hanging means at the lower part thereof, said support member having an upper 45 end perforated for mounting the same and having a pair of parallel slots above the flag hanging means adapted to accommodate a conventional moulding picture hanging hook for mounting the flag holder with its pendant flag upon a moulding.

10. The combination of a flag and a holder unit therefor, said holder unit comprising a flagstaff finial having a support member of sheet material secured to the rear face thereof, said unit 55 having a recess in front of the lower part of said support member, said member including upstanding flag hanging tongue means unitary therewith, the upper corner of said flag extending into said recess between the finial and the hanging tongue means, and being suspended from said tongue means, said support member having means for mounting the unit against a wall.

11. A unit for hanging a flag from the wall, 65 said unit comprising a flagstaff finial, and a support member, the latter of sheet material, affixed to the rear of said finial, the upper part of said support member serving as a finial hanger, the lower part of said support member being behind the lower part of the finial and spaced therefrom, and having a tongue formation to serve for hanging a flag by its corner accommodated in said space.

CHARLES H. FORBELL.
